UNITED STATES PATENT OFFICE.

MILTON A. MCKEE, OF WESTERLY, RHODE ISLAND, ASSIGNOR TO C. B. COTTRELL & SONS COMPANY, OF NEW YORK, N. Y., A CORPORATION OF NEW JERSEY.

STEREOTYPE.

No. 885,948.

Specification of Letters Patent. Patented April 28, 1908.

Application filed December 28, 1906. Serial No. 349,827.

To all whom it may concern:

Be it known that I, MILTON A. MCKEE, a citizen of the United States, residing at Westerly, in the county of Washington and 5 State of Rhode Island, have invented certain new and useful Improvements in Stereotypes; and I do hereby declare the following to be a full, clear, and exact description of the invention, such as will enable others skilled 10 in the art to which it appertains to make and use the same.

My invention relates to printing blocks and processes of producing them, and especially to stereotypes. 15 The invention contemplates the production of a stereotype plate in whose printing surface shall be incorporated graduated planes of elevation and depression corresponding with the several tones, dark, intermediate, and light, of the picture or delineation.

The object of the invention is to produce by the introduction of a new step in the usual process such a stereo plate having its printing 25 surface in different planes according to the various tones of the picture or delineation, parts of the printing surface being raised to correspond to the darkly shaded parts of the subject to be printed and other parts of the 30 printing surface being relatively depressed to correspond to the lightly shaded parts of the subject to be printed, and to thereby dispense with the customary "cut overlay" on the impression cylinder of the printing press.

With the ordinary flat plate having its printing surface in one plane the effect of differentiated pressure upon the various tones has been hitherto produced by the use 35 of what is known in the art as a "cut overlay." This cut overlay is made of superimposed sheets of paper so arranged that its body is of varying thickness. It is applied to a portion of the platen or impression cylinder to register during the act of printing with 40 the printing surface of the plate, whereby those parts of the paper upon which are to appear the relatively darker portions of the print are forced with relatively greater pressure against the darker printing tones of the 45 plate.

In the formation of the cut-overlay from proofs of the illustration or delineation the high lights are first cut out and discarded

leaving a base sheet. Upon the base sheet is placed the next sheet from which has been 55 cut out and discarded the high lights or lightest tones and also the next lightest tones, and so on until in the last proof sheet all but the solids or darks are cut out and discarded, so that the overlay is thickest at the solids 60 and thinnest at the high lights and proportionate at the intermediate tones. This work is the principal part of the "make-ready" or making the press ready, and may be the whole of it in many instances. 65

Briefly then, the object of the invention is to do away with this cut-overlay in the use of stereotype plates by graduating the printing surface to put the "make-ready" into the surface of the plate and to do this by a simple and efficient process.

In the practice of producing stereotype plates there is made first a "flong" by combining a series of tissues and backing sheets into one body sheet. The flong in a damp 75 state is laid upon the printing surface of the form and beaten in, in the usual way to all portions of the form below the printing surface, being thus converted into a matrix possessing the character of the face of the form, 80 but, of course, in reverse. This matrix or mold is then placed in a stereo-casting box and molten metal is poured into the casting box and over the matrix, producing a replica or facsimile of the form. The printing surface of the plate so cast, the familiar stereotype plate, is substantially level in plane, 85 those parts corresponding to the darkest, lightest and intermediate shades of the subject having the same level. 90

If the plate were printed from directly pressure would be exerted upon all tones of the plate with equal force. Printing thus and without any differentiation in the application of the pressures would result not only 95 in defective prints, but also in the destruction of the face of the stereo-plate because while the darks or solids would stand great pressure the application of equal pressure to the lighter and intermediate tones would, 100 obviously, be destructive in view of the character of the plate, whose printing surface is made up of a multitude of points or dots relatively close and compact in the solids, open or scattered in the high lights and proportionate in the intermediate tones. These 105

results are avoided, as previously indicated, by the application of cut-overlays to the impression cylinder of the printing press to properly distribute the pressure so that it shall be greatest upon the solids or black printing parts, least upon the high lights, and in proportion upon the intermediate tones. This part of the make-ready, or the preparation of the cut-overlay, even in magazine, book work, and high class printing, is a matter of much time and expense and is so serious a factor that it can be applied, practically, only in the highest and most expensive classes of printing. It is, on account of the time required, impracticable in the rush of newspaper work to apply such make-ready to the impression cylinder. The almost universal application of half-tone plates, with which this invention is especially concerned, has made these conditions generally understood in the printing art. I not only put this make-ready into the face of the stereotype plate itself, but I also do it by a process coincident with the process generally employed in the production of the stereo-plate, so that when the plate is produced it is ready for printing without further treatment and without delaying the press for the application of the equivalent make-ready. In advance and to be thus in readiness, I make from proofs what I may term a "reverse overlay." That is to say, instead of making this overlay with the highest parts corresponding to the darks or solids of the plate and the lowest parts corresponding to the light or highest tones, and so on, I reverse the character of the overlay, making the thickest part correspond with the highest lights of the pictures and the thinnest parts with the darks of the picture, or, briefly, I make the elevations of this overlay to correspond with the high lights and so on intermediately. I then prepare the matrix by beating in the damp flong upon the form as previously described and then apply this reverse overlay to the back of the matrix while it is yet in contact with the face of the form, so that, for example, the greatest elevations and the greatest depressions of the reverse overlay correspond respectively with the high lights and solids of the illustration or delineation on the form. The reverse overlay is pasted down firmly to the beaten in sheet and, preferably, in order that the complete matrix may possess the usual standard body, another backing sheet should be applied. I then have a matrix which carries on its back the reverse overlay and, in the example stated, a backing sheet over the reverse overlay. The matrix being properly dried is ready for the casting of the plate, it being understood from the previous description that the matrix is now thickest or deepest where the lightest tones occur upon its surface and thinnest where the dark-

est tones occur, so that when the stereotype plate is cast upon the matrix it shall have in its face the desired make-ready which will be in opposition to the graduated planes of the matrix. The matrix after passing through the customary drying operation as indicated, is then placed in the casting box, either flat or curved, and the molten metal is poured in or forced in by the aid of a pump. The combined heat, weight, and impulse forces the molten metal into every depression in the face of the matrix. The thinnest part of the matrix yields and is forced back to a seating against the rear side or bottom of the casting box while those parts of the matrix bearing the several layers of the overlay and the elevations of the overlay, are relatively supported during the casting process. The matrix is really transformed from one having elevations and depressions in its back to one having elevations and depressions in its face, producing a corresponding cast. The resulting stereo plate when taken out and finished in the usual manner possesses in its printing surface depressions and elevations accurately predetermined and regulated by the matrix and is at the same time even and level on the back whether a flat or a curved plate. The matrix is a reverse of the form and carries a reverse overlay. Therefore in correspondence with it, the resulting stereo-plate will, of course, be a reverse of the matrix and its overlay and will be a replica or facsimile of the form, with the addition of relative elevations and depressions in its printing surface.

Another mode of describing the matrix is to say that it has formed in or on its back graded elevations corresponding in order with the high lights and intermediate tones of the subject on the face of the matrix, so that the resulting cast or stereotype shall have graded elevations in its printing face corresponding with the darks or solids and intermediate tones of the subject the higher elevations corresponding with the dark tones. And again, the fact that when the reverse overlay is fixed to the back of the matrix it is then the back of the matrix and substantially integral with the matrix, provides another definition in that the matrix has formed in its back graded depressions corresponding respectively with the darks or solids and the intermediate tones of the subject on the face of the matrix. It will also be observed that the matrix has a level face and a level back and that the face is supported by the body of the matrix at those parts which correspond to the high lights of the object on the face of the matrix, so that there are depressions intermediate the face and back of the matrix. Of course in a subject having but two tones there would be no "intermediate" tones, but for convenience I have referred in the illustration employed to sub-

jects having more than two tones. In a plate so treated the high lights or those printing parts or tones which usually wear out the soonest in use will be protected because they 5 are depressed in plane. The solids, or those printing parts usually lacking sufficient pressure will receive it because they are elevated in plane. In other words the dark printing tones of the illustration or delineations receive the greatest printing pressure while the light printing tones are relieved of printing pressure. This adds materially to the life 10 of the plate, and does away with the expensive and time-consuming make-ready upon 15 the impression cylinder.

It will thus be observed that my process does not vary from the usual process of producing a stereo plate excepting that at a certain point in that process I apply to the matrix 20 a reverse overlay and, preferably, a backing. In short, I place a reverse overlay within the structure of the matrix during the course of carrying out the usual process of producing a stereotype plate and thereby 25 secure as a result a stereotype plate having in its printing surface elevations and relative depressions corresponding with the darks or solids and the high lights and intermediate tones of the picture or delineation to be 30 printed.

A simple illustration of this process and the resulting product is given in the accompanying drawings in which

Figure 1 represents the backing, the reverse overlay, the flong and the form in their relative order to carry out the process; Fig. 2 represents the flong applied to the form, the reverse overlay to the back of the matrix, and the backing to the back of the reverse 35 overlay. Fig. 3 represents the matrix with its face uppermost and the reverse overlay and backing applied to it, that is the original and the supplemental or secondary matrix combined to form the new matrix; Fig. 4 represents the matrix, reverse overlay and backing combined to form a new matrix resting upon the bottom or side of a stereo casting box into which the metal has been poured so that the metal has run into all the 40 indentations or cisions of the face of the matrix and has also forced the matrix down into the depressions of the reverse overlay; Fig. 5 represents the complete stereotype 45 plate having elevations and depressions in its printing surface corresponding with the tones of the picture or delineation desired, and even and level on its back.

I have for convenience illustrated the parts by horizontal or flat sections, such illustrations being more appropriate also in view of the fact that the drawing is of a diagrammatic nature.

In the accompanying drawings 1 represents a form; 2 a flong; 3 a reverse overlay; 5 and 4 a backing. These are shown as before

indicated in Fig. 1 in their relative positions. The flong is shown as made up of two tissues and a body sheet, the tissues being indicated by the lighter lines and the body sheet by the heavier line above. The flong 2 is placed 70 upon the face of the form, here shown in section, and is then beaten into the form resulting in the formation of a matrix 5 which bears on its back, secured to it, a reverse overlay and backing, or what might be briefly 75 termed a matrix having elevations on its back.

6 represents a stereo casting box and 7 represents the molten metal which has been run in upon the face of the matrix.

In the drawings, for example Fig. 4, I have illustrated the greatest elevation at 8, the next 9 and the least 10 of that part of the reverse overlay to the left of Fig. 3. At 11 I have indicated a cut out portion which with 80 relation to the other parts may be called a depression. When the molten metal is poured in upon the matrix with its attached reverse overlay and backing resting upon the bottom or side of the stereo casting box as 85 illustrated in Fig. 4 the part of the matrix at the extreme left, for example, will be depressed to correspond with the steps made by the planes 8, 9 and 10. This is shown, for example, in Fig. 5 where reference numeral 90 20 indicates the stereo plate having graduated planes in its surface. At the extreme left it will be observed that the first step 21 is lower than the elevations 22 and 23 and that it coincides, for example, with the elevation 24. There is then one step immediately below the step 21, and, finally, the lowest step at 25 corresponds with a similar 95 step at the other end at 26. It will be observed as hereinbefore indicated that these 100 steps of the stereo plate 20 are in reverse of the back of the matrix 5. The lowest parts are the depressions 25 and 26, for instance, being formed by the settling of metal under pressure on each side of the elevation 8, in graduation upward as indicated. It will be understood that all of these drawings are 105 exaggerated in outline and that, of course, no stereo plate will exhibit to the eye the various tones of a picture or delineation as illustrated for convenience in Fig. 5.

In this specification I have used the phrase "picture or delineation" as a generic term covering any printing effect secured by varying tones, shades or colors. For example, 110 my invention is applicable to the production of a stereotype having varying size type faces, or light, medium and black faced types, and also, for example, for rounding a plate or its edge to prevent blurring. In short, it is 115 broadly applicable to create elevations and depressions in the face of the plate to properly differentiate pressures in printing.

What I claim is:

1. The herein described process of produc- 120

ing stereotypes which consists in first forming a matrix, then applying to the back of the matrix an overlay, and then casting.

2. The herein described process of producing stereotypes, which consists in making a matrix, making a reverse overlay from proofs of the subject to be printed, and applying it to the back of the matrix, and then casting.

10 3. The herein described process of producing stereotypes, which consists in making a matrix, then applying to the back of the matrix elevations and depressions corresponding respectively to the high lights and 15 dark or solids of the subject upon the face of the matrix, and then casting.

4. The herein described process of producing stereotypes, which consists in applying a flong to a form, then applying to the back of 20 the resulting matrix resting on the form an overlay, then removing the combined matrix and overlay, and casting.

5. The herein described process of producing stereotypes, which consists in placing a flong upon a form, beating in to form a matrix, fixing to the back of the matrix resting 25 on the form an overlay having elevations and depressions corresponding respectively to the high lights and the darks or solids of subject 30 upon the face of the form, placing a backing sheet over the overlay, removing the matrix, and casting.

6. The herein described process of producing stereotypes, which consists in making a 35 matrix, forming on the back of the matrix elevations corresponding respectively with the high lights and intermediate tones of the subject on the face of the matrix, and casting.

7. The herein described process of producing stereotypes which consists in taking an impression or matrix of a form, applying the face of a reverse overlay to the back of the impression or matrix and then casting upon the face of the impression or matrix.

45 8. The herein described process of producing stereotypes, which consists in making a matrix, forming in the back of the matrix depressions corresponding respectively with the darks or solids and the intermediate tones of 50 the subject on the face of the matrix, and casting.

9. The process of making a stereotype plate, which consists in forming a matrix with graded elevations on its back or graded 55 depressions in its back, and then flowing metal upon the face of the matrix so that the metal will force down the body of the matrix until it is supported at all the different levels.

10. The process of making a stereotype 60 plate, which consists in casting the plate and by the same act altering the face of the ma-

trix so that relative elevations and depressions corresponding with the tones of the subject are formed in the plate.

11. The process of making a stereotype 65 plate, which consists in casting the plate upon a matrix and by the same act forming relative elevations and depressions in the face of the matrix and the face of the plate.

12. The process of making a stereotype 70 plate, which consists in forming a matrix with elevations and depressions in its back, then pouring metal upon the face of the matrix, thus carrying down the face of the matrix to transform the matrix into one having 75 elevations and depressions in its face and at the same time forming complementary depressions and elevations in the face of the cast plate.

13. The process of making a stereotype 80 plate, which consists in forming a matrix with a yielding face that is, with a face partly supported and partly unsupported and then casting upon the face of the matrix to form relative elevations and depressions in 85 the face of the plate.

14. The process of making a stereotype plate, which consists in forming a matrix of varying thickness, then casting upon the face of the matrix and depressing the face at all 90 points except the thickest.

15. As a new article of manufacture, a matrix for casting printing blocks, having on its back elevations corresponding with some of the tones of the subject. 95

16. As a new article of manufacture, a matrix for casting printing blocks, having in its back depressions corresponding with some of the tones of the subject.

17. As a new article of manufacture, a matrix for casting printing blocks, having on its face the subject of the form from which it was made in reverse and on its back a reverse overlay of the subject.

18. As a new article of manufacture, a matrix for casting printing blocks having on its back elevations and depressions corresponding respectively to the high lights and solids of the subject on the face of the matrix.

19. A matrix having a level face a level 110 back and intermediate elevations and depressions.

20. A matrix having a level face supported by the body of the matrix opposite the high lights of the subject on the face. 115

In testimony whereof I affix my signature, in presence of two witnesses.

MILTON A. MCKEE.
